BEDROOM NIGHT LAMP OR SIMILAR ARTICLE

Otto Murray Summers, Philadelphia, Pa.

Application February 24, 1959, Serial No. 54,712

Term of patent 14 years

(Cl. D48—20)

FIG. 1

FIG. 2

FIG. 3

FIG. 4

Fig. 1 is a side elevational view of a bedroom night lamp or similar article, showing my new design;

Fig. 2 is a top plan view thereof;

Fig. 3 is an end elevational view thereof looking at the right end of Fig. 1 with the card and plug omitted for convenience of illustration; and

Fig. 4 is a vertical section taken on line IV-IV of Fig. 1, but omitting the lighting apparatus housed in the bedroom night lamp or similar article.

The dominant features of my design reside in the portion shown in full lines.

I claim:

The ornamental design for a bedroom night lamp or similar article, as shown and described.
